UNITED STATES PATENT OFFICE.

ALEXANDER L. MAXWELL, OF DETROIT, MICHIGAN.

REAMER FOR THREAD-CUTTERS.

No. 926,272.

Specification of Letters Patent.

Patented June 29, 1909.

Application filed December 17, 1908. Serial No. 468,054.

To all whom it may concern:

Be it known that I, ALEXANDER L. MAXWELL, a citizen of the United States, residing at Detroit, county of Wayne, State of Michigan, have invented a new and useful Improvement in Reamers for Thread-Cutters, of which the following is a specification.

The present invention relates to a reaming attachment for pipe thread-cutters, by which burs and ragged edges may be removed from the interior of the pipe at its ends at the same time that the thread is being cut. There have been such devices proposed heretofore, but in all of them, so far as I am aware, there has been a multiplicity of parts, such as to render the cost of production excessive and to require much manipulation and adjustment in their use. To overcome these objections, I have provided a device which is extremely simple in construction and which may be readily adjusted for service or swung out of the way, without detachment from the cutter, when not in use.

The specific character of the invention will be best understood upon reference to the following description taken in connection with the accompanying drawing, and the scope of the invention will be pointed out in the appended claims.

In the drawing, Figure 1 is a perspective view of the reaming attachment; Fig. 2 is a plan view of a pipe thread-cutter with the reamer in position thereon; and Fig. 3 is a side elevation of the same with parts broken away.

In these figures, corresponding parts are designated by the same characters.

As will be seen from an inspection of Fig. 1, the reamer, which may be designated generally A, is composed of a single piece of metal, preferably steel, bent so as to bring its opposite ends at substantially right angles to each other and having the one slotted for attachment to the die stock, and the other shaped and tempered so as to provide cutting edges for removing the burs and ragged edges from the interior of the pipe. The cutting end of the reamer is preferably shaped with pyramidal faces 11 and intervening cutting edges 12. As here shown, four such faces are provided and this arrangement is particularly advantageous when it is desired to sharpen the reamer, since each face may be pressed against an emery-wheel or grindstone and the required

sharpness of the edges obtained. This arrangement is of distinct advantage, since such grinding implements are more readily available than those necessary to sharpen more complicated cutters. The attaching end 13 of the reamer is provided with a relatively large flat bearing surface which gives stability to the device when in position on the thread-cutter. The slot 14 is provided for the passage of the attaching bolt and permits the reamer to be centered upon the cutter.

In Figs. 2 and 3, a thread-cutter B of a well-known type is illustrated. It comprises the die stock 15 with the usual handle 16 and dies 17, 18, together with the bracket 19 and collar 20 for the guidance of the pipe such as 21, upon which the thread is to be cut. The collar 20, which is selected according to the size of pipe to be operated upon, is held in the bracket 19 of the die stock by a suitable thumb-screw 22. The dies 17, 18 are provided with slots, shown by dotted lines in Fig. 2, through which suitable bolts 23, 24 pass into threaded engagement with the die stock. They are suitably adjusted before screwing the bolts 23, 24 home, by adjusting screws 25, 26, passing through lugs 27, 28 upon the stock.

As here illustrated, the reamer A is attached by the bolt 23 which passes through the die 17. As the die stocks are purchased in the market, the die 17 is secured in place by a bolt of the same length as the bolt 24; and in order to provide for attaching the reamer, it is only necessary to provide a somewhat longer bolt. The position of the reamer may be adjusted toward and from the die stock by washers or nuts placed between the end 13 and the adjacent die, thereby adapting it for pipes of different diameters. In the present instance, a single washer 29 is shown in position at this point, but obviously other washers or nuts might be provided to give this adjustment. The reamer may be readily adjusted with reference to the center of the pipe by reason of the slot 14.

In the operation of the device, as is well known, the cutter and reamer occupy the position upon the pipe illustrated in Fig. 3; and as the handles are grasped by the operator and the whole is rotated, the thread is cut and the end of the pipe reamed out. When it is desired to use the cutter without the reamer, the latter may be swung out of the way by simply loosening the bolt 23, rotating

the reamer to, say, the dotted line position, and then tightening up the bolt 23 again.

It will be seen from the above that the reaming attachment I have produced is small and of relatively simple construction and may be put into position for service, adjusted, or sharpened with a minimum of labor and with devices readily available to workers in this art. The die stock here illustrated is 10 that known to the trade as the Armstrong die stock, but the attachment is obviously applicable to other stocks of similar construction.

What I claim as new and desire to secure 15 by Letters Patent of the United States is:—

1. A reaming attachment for pipe thread-cutters comprising a single member terminating at one end in pyramidal faces having cutting edges and at the other end in a flat 20 slotted portion extending substantially at right angles to the axis of the pyramid formed by said faces.

2. The combination with a pipe thread-cutter comprising a suitable die stock and flat dies adjustably mounted thereon, of a 25 reaming attachment comprising a single member having a free end disposed so as to enter the end of a pipe passing between the dies of a cutter and provided with suitable cutting edges for removing burs from the interior of the pipe, and having a flat slotted end extending substantially at right angles to the free end and adapted to lie substantially parallel to one of said dies, a bolt for connecting the attachment and adjacent die 30 to the die stock, and means for adjusting said attachment toward and from said die stock.

In witness whereof, I hereunto subscribe my name this 11th day of December, 1908.

ALEXANDER L. MAXWELL.
